US0D1017607S

(12) **United States Design Patent** (10) **Patent No.:** **US D1,017,607 S**
(45) **Date of Patent:** **** Mar. 12, 2024**

(54) **KEYBOARD**

(71) Applicant: **Yuqing Xie**, Dongguan (CN)
(72) Inventor: **Yuqing Xie**, Dongguan (CN)
(*) Notice: Patent file contains an affidavit/declaration under 37 CFR 1.130(b).

(**) Term: **15 Years**

(21) Appl. No.: **29/865,233**

(22) Filed: **Jul. 15, 2022**

(51) LOC (14) Cl. **14-02**

(52) U.S. Cl.

USPC **D14/392**

(58) **Field of Classification Search**

USPC D14/247, 320, 331, 333, 338, 346-347,

(57) **CLAIM**

The ornamental design for a keyboard, as shown and described.

DESCRIPTION

FIG. 1 is a perspective view of a keyboard showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 shown in FIG. 2;

FIG. 11 is an enlarged view of portion 11 shown in FIG. 2;

and,

FIG. 12 is an enlarged view of portion 12 shown in FIG. 3. The dash-dash broken lines in the drawings depict portions of the keyboard that form no part of the claimed design. The dot-dash broken lines represent boundaries of the enlarged portions and form no part of the claimed design.

1 Claim, 12 Drawing Sheets
